UNITED STATES PATENT OFFICE.

AUGUSTUS FREEBORN BROWN, OF HAVRE DE GRACE, MARYLAND, ASSIGNEE TO GORRELL STEEL SPIKE LOCK RAILROAD TIE CORPORATION, OF HAVRE DE GRACE, MARYLAND, A CORPORATION OF MARYLAND.

METALLIC RAILWAY-TIE AND FASTENING.

1,115,167.

Specification of Letters Patent. Patented Oct. 27, 1914.

Application filed August 14, 1914. Serial No. 856,794.

To all whom it may concern:

Be it known that I, AUGUSTUS FREEBORN BROWN, a citizen of the United States, residing at Havre de Grace, in the county of 5 Harford and State of Maryland, have invented certain new and useful Improvements in Metallic Railway-Ties and Fastenings, of which the following is a specification.

My invention relates to a metallic railway-10 tie and rail fastening, and the invention consists, essentially, of a railway-tie formed of a single piece of metal having on the upper surface near the end, suitable seats for the rails, said tie being, also, integrally 15 formed below the sides of each rail seat, with a pair of vertically-disposed spaced boxes which are closed on all sides except the top and bottom and having opposite interior walls fashioned sinuous or with alternate 20 projections and depressions whereby a serpentine channel is formed for the reception of the spikes which secure the rails to the tie.

My invention furthermore specifically 25 consists of a metal tie formed integral with a horizontal base flange and a flange arranged perpendicularly thereto and extending longitudinally along the central portion of the base flange, said perpendicular flange being 30 widened on its upper surface near each end to form a seat for a railway rail, and said perpendicular flange being integrally formed below the sides of each of said rail seats with a vertically extending spike receiving box- 35 ing, having opposite interior walls made sinuous for the purpose of distorting the rail securing spike during the driving of the same into the tie whereby the spike becomes securely locked in place.

40 My invention also consists in making each spike receiving box of greater horizontal width than the diameter of the spike it is to admit, to enable said spike receiving box to receive a shim or like part, which may be 45 normally substantially straight and which is introduced into the box against a sinuous wall thereof, whereby the shim is distorted and made to conform substantially to the wavy surface of the wall simultaneously 50 with the driving of the spike and the distortion of the same.

My invention also consists of the parts

and the constructions, arrangements and combinations of parts which I will herein- 55 after describe and claim.

In the accompanying drawing forming part of this specification and in which similar reference characters indicate like parts in the several views, Figure 1 is a perspective view of a railway-tie embodying my invention, showing rails thereon in dotted lines; Fig. 2 is a top plan view, and Fig. 3 is a longitudinal sectional view, on the line 60 $y-y$ of Fig. 2.

In the said drawing A represents a rail- 65 way-tie formed entirely of metal and, preferably, as a single casting. Specifically, the tie consists of a base flange a of suitable width and a flange b which, when the tie is in position, extends perpendicularly to the base flange and rises from the center thereof and extends from end to end of said base flange. For the sake of lightness and at the same time to give added strength to the tie, the vertical flange b thereof may be formed with 70 openings c at the ends and intermediate portions, as is well known in the art.

The upper portion of the vertical flange b , near each end, is widened transversely by casting or otherwise forming the same with 80 horizontal flanges d which extend for a suitable distance along the longitudinal sides of the flange to form a seat and support e for the usual railway rail B. At the outer sides of the rail seats e , the vertical flange b of the 85 tie, is also formed integrally with vertical shoulders f against which abut the outer edges of the horizontal base flanges of rails and by which lateral outward spreading of the rails is prevented.

90 If desired, the central portions of the rail seats e may be formed with openings g ; and the vertical flange of the tie beneath said seats as well as the portion of the base flange vertically in line with said rail seats, may 95 be formed with openings h , h' respectively, but this construction is optional and forms no essential part of my present invention.

A leading feature of the present invention is in casting or otherwise integrally forming the tie with vertical boxes C, located at opposite sides of and vertically below each rail seat, said boxes being closed on all sides except the top and bottom, the vertical

flange of the tie at this point being slightly flared transversely to enable the boxes to be satisfactorily formed in the relatively thin edgewise standing flange *b* of the tie. The 5 interior of each box *C* is cast with two opposite walls *c*, which are made sinuous or with alternate curved projections and depressions.

Each of the boxes forms a spike receiving 10 recess of serpentine form, into which the ordinary and substantially straight railway spike is designed to be driven and to be distorted during the driving operation, whereby the spike is made to substantially 15 conform to the wavy outline of the walls of the box against which the spike is forced as it is driven into place. The sinuous walls of the boxes, therefore, give a corresponding wavy form to the spike, which greatly adds to the 20 security with which the spike is held. These walls also have the function of again straightening the spike when the same is withdrawn.

When it is desired to adjust the rails inwardly to take up or compensate for wear of the treads of the rails, I employ suitable metal shims *D*, which may be normally straight and which are placed in the boxes against one of the sinuous walls thereof, 30 whereby upon driving the spike in place the shim is crowded against and into the curvatures of the wall and is thereby so distorted as to make it conform substantially to the wavy surface thereof; at the same time the 35 spike, which is confined between the shim and the opposite sinuous wall of the box, is distorted and made to conform substantially to the formation thereof and also to that of the distorted shim.

40 Having thus described my invention, what I claim as new and desire to secure by Letters Patent is:

1. A metallic railway tie having a vertical flange extending longitudinally thereof, said flange being formed integrally with rail seats and interior spike receiving boxes, said boxes being disposed at the sides of said seats and extending toward the base of the flange and having opposed interior walls of 45 sinuous form adapted to distort normally substantially straight spikes when the lat-

ter are forcibly driven into the boxes while in engagement with said walls.

2. A metallic railway tie having a horizontal base flange and a flange at right angles thereto, and extending longitudinally along the same, said vertical flange having its upper edge, near the ends, formed with horizontal oppositely projecting flanges 55 constituting widened rail seats, said right-angled flange being formed interiorly with integral spike receiving boxes, each having opposed sinuous walls adapted to distort a spike simultaneously with the driving of the same into the box, whereby the spike is 60 made to conform substantially to the wavy outline of said walls.

3. A metallic railway tie having a vertical flange formed with rail seats and interior integral spike receiving boxes, said 70 boxes being vertically disposed at opposite sides of the rail seats and each having opposed sinuous inner walls, adapted to distort a spike forcibly driven into said boxes, whereby the spike is made to substantially 75 conform to said walls.

4. In combination, a metallic railway tie having a vertical flange extending longitudinally thereof, said flange being formed with interior spike receiving boxes whose 80 walls are integral with the flange, said walls being sinuous and adapted to distort a spike driven forcibly past them, a spike, and a metal shim introduced between the spike and one of the sinuous walls of a box 85 and adapted to be distorted by and in unison with the distortion of the spike.

5. A railway tie having a flange standing on edge and the interior of the flange near the ends being formed with spike receiving 90 boxes, the walls of the boxes being integral with the flange and certain of said walls being formed in the flange and being sinuous and adapted to distort a spike driven forcibly into the box in contact with said sinuous 95 walls.

In testimony whereof I affix my signature in presence of two witnesses.
